UNITED STATES PATENT OFFICE

ALEXANDER WEINBERG, OF NEW YORK, N. Y.

GAME APPARATUS

Application filed December 12, 1929. Serial No. 413,581.

My invention relates to games or amusement devices in which a ball or missile is used, both in solitaire and social games. And my object is two-fold, viz:—first, the provision of a ball propelling or driving device that will enable a great variety of blows or strokes to be administered, and involve the exercise of skill; and, second, the provision of a game board with characteristics of layout and construction that cooperate with said driving or propelling device.

My invention consists in whatever is described by or is included within the terms or scope of the appended claims.

15 In the drawings:—

Fig. 1 is a perspective view of game apparatus embodying my invention both as to the propelling device or propeller and the board;

20 Fig. 2 is a cross section thereof;

Fig. 3 is a perspective view of the ball propeller;

25 Fig. 4 is a horizontal section thereof, with balls shown in dotted lines to illustrate some of the strokes that are possible.

My propeller is a rotary device that comprises a stem or shaft, 10, having a handle portion at one end for convenient grasping by the fingers or hand, and at the other end 30 having or forming a center or pivot, 11, about which the propeller, resting on a bearing surface, may be partially revolved, and also having at or adjacent the pivot end, a radial wing or wings to engage the ball in play. Preferably, there are two such wings, 12, that are diametrically opposite, each being blade-like with one or both sides flat and standing vertically, or substantially vertically when in ball-engaging position to project the ball in a more or less horizontal direction, over the surface of the game board on which the ball 35 is played.

40 Preferably each wing is adjustably connected with the stem or shaft, 10, to enable its ball-striking face to be set at an angle, if desired, so that, for example, it may give a lift to the ball when it strikes it, to cause the ball to move in a curve or trajectory which will carry it over obstacles on the game board, or to increase the distance of the stroke. In

this case, the striking surface will be slightly oblique to the direction of swing or turn of the propeller on its axis. To this end, each wing has at its inner end a round stem, 13, which snugly fits a round hole in the stem, 13, so that it will be held friction tight against accidental turning, but may readily permit turning of the wing by such force as can be applied by the fingers. An excellent arrangement is to bore a diametrically extending hole 45 through the stem or shaft, and to place in it a split spring metal tube, 14, which is slightly larger in diameter than the hole so as to require compression to thrust it into the hole to cause it to grip the walls thereof. The stem, 13, inserted in the tube, 14, is gripped thereby with the desired pressure to hold the wing 50 force at the desired angle.

The bearing center or pivot, 11, may be a convexly rounded block of rubber, or other material, or it may be a suction cup of rubber, with enough lateral flexibility in its connection with the shaft, 10, as to permit the placing of the latter at the most advantageous slant or angle for driving the ball. And 55 preferably the pivot or fulcrum end of the propeller is the heavier, so that its momentum or force may thereby be increased when turned to drive the ball.

60 In using the propeller, its shaft, 10, is grasped between fingers and thumbs (if small enough for that) and its pivot or fulcrum end placed against game board or other surface on which the ball rests, and in that position relative to the ball, which in the judgment of the player, will enable the wing to engage the ball to propel it in the desired direction. This may, as shown in Fig. 4, exert force on the ball at the outer end or tip 65 of the wing so as to cause the ball to spin 70 or rotate on its axis and thus result in a curved ball, or a ball that moves in a curved path. Or the ball may be engaged further inward of the wing and receive no turning impulse. The axis of the shaft, 10, may be 75 vertical, or oblique, or slanting. By pressure exerted endwise on the shaft, its pivot, 11, will be friction resist turning and so by the extra effort made by the player to turn the shaft, and the sudden release of the end- 80

wise pressure, the player may exert considerable propelling pressure on the ball.

By having two wings, 12, diametrically opposite, the propeller is balanced on its shaft axis, and the ball may be engaged when lying on either side of the propeller, without turning the latter wholly around from side to side.

In a social game, as in the simulation of lawn tennis, or hockey when there are two adversary players, each with a propeller, it is desirable to stop or check a delivered ball, and to provide for that action or play, one side of each wing may have a ball cup or catcher, 15, that may consist simply of a V-shaped pocket fastened to the wing at its apex, with a space between the diverging sides of the V of a size to receive the ball and prevent its glancing off the wing, as it would do if it struck a plane, flat face.

The game board shown in Figs. 1 and 2 is specially suited for use with my propeller, but I, of course, do not limit myself to the propeller per se with any one game board. The game board shown has a flat, oblong table, 16, with cups or pockets of various kinds spread over its surface, and at opposite sides it has an upwardly and outwardly inclined flange, 17, to which one or more traps or pockets are secured. Said traps or pockets are each a curved wire, 18, with a leg, 19, at each end that is attached to the flange at separated points lengthwise thereof, with the wire, 18, spaced above the flange, so as to form a basket with an open side and top, and at an angle, or incline, into which a ball may be thrown by the propeller acting board. By reason of the great flexibility in the application of the propeller to the ball, it is possible to make the somewhat difficult play required to cast the ball into the basket. The basket has a length to hold several balls at a time, and spaces are numbered so as to give a score value to each ball retained in the basket. For example "5" for one ball, "10" for two balls; and "20" for three balls.

On the plane or flat area of the board are several solid walled cups, 20, each marked with a score value, and several open wall cups, each formed by spaced pegs or posts, 21, that are made of coil springs, so that they are flexible and resilient to add to the difficulty of placing a ball in the cup so formed, for if the ball strikes a flexible post, 21, it may rebound therefrom.

The far corners of the game board may be concavely curved to provide surfaces for carom plays of the balls.

My propeller may be made of a size to play balls of two or more inches in diameter, and in that case, the handle part of the shaft may have radial arms for grasping by the hand to rotate the propeller.

With the complete apparatus shown in the

drawings, the point of the game whether one person plays or several play, the player positions the ball at the starting point as shown in Fig. 1 and then by means of the propeller endeavors to drive the ball into any selected one of the pockets and the numerical value of the pocket in which he happens to place the ball is noted, and at the conclusion of the number of plays determined on the sum of the values of the various pockets is taken as the score. When two or more persons play the one making the highest score will be the victor.

What I claim is:—

1. A missile propeller comprising a shaft having a handle end and a pivot end, and a blade-like, flat-sided missile-contacting member extending radially outward from the shaft adjacent the pivot end the flat side of the member extending radially and axially of the shaft, and the shaft being rotatable on its pivot end by a twirling motion exerted by the fingers on the handle end thereof.

2. A missile propeller comprising a shaft having a handle end and a pivot end, and oppositely projecting flat-sided, blade-like missile-contacting wings adjacent the pivot end.

3. A missile propeller comprising a shaft having a handle end and a pivot end, and a blade-like oblong missile-contacting member extending radially outward from the shaft having a plane missile-contacting face.

4. A missile propeller comprising a shaft having a handle end and a pivot end, and a blade-like, flat-sided missile-contacting member extending radially outward from the shaft having a plane missile-contacting face, adjustable to different angles in relation to the axis of the handle.

5. A missile propeller comprising a shaft having a handle end and a pivot end, and a missile-contacting member extending outward from the shaft having on one side a plane face, and on an opposite side a cup.

6. Game apparatus comprising a missile propeller and a board providing a support for the latter having an upwardly and outwardly inclined, basket supporting surface on the margin thereof said board having a plane missile directing surface leading to the inclined margin thereof.

In testimony whereof I hereunto affix my signature.

ALEXANDER WEINBERG.
